BOXER'S HAND PROTECTOR

Filed Oct. 5, 1927

Patented Mar. 26, 1929.

1,706,503

UNITED STATES PATENT OFFICE.

GORDON TRAVERS, OF LOS ANGELES, CALIFORNIA.

BOXER'S HAND PROTECTOR.

Application filed October 5, 1927. Serial No. 224,032.

My invention relates to a hand and wrist portector for boxers and has for its principal object the provision of a padded and reinforced glove-like member that is adapted to be worn by boxers particularly while training, and which glove or protecting device is especially designed for the portection of the hands and wrists.

During training periods and particularly 10 while punching an inflated or padded bag there is danger of injury to the hands, knuckles and wrists of the boxer, and it is the purpose of my invention to provide padded glove-like members that cover the hand, 15 thumb and wrist of the wearer, and which padded members are reinforced so as to offer a relatively high degree of protection to the various joints of the hand, and wrist, thereby minimizing danger of injury to the hands of 20 the wearer during training periods.

A further object of my invention is to provide a hand protecting device of the character referred to that will enable the hand of the wearer to be readily closed or clinched, 25 and likewise enable the end of the thumb to be readily turned inward when the hand is closed.

With the foregoing and other objects in view, my invention consists in certain novel features of construction and arrangement of 30 parts that will hereinafter be more fully described and claimed and illustrated in the accompanying drawing, in which—

Fig. 1 is a view looking against the inside or palm portion of a hand protecting device of 35 my improved construction.

Fig. 2 is a view looking against the rear or back side of the hand protector.

Fig. 3 is an enlarged cross section taken on the line 3—3 of Fig. 2.

Fig. 4 is an enlarged section taken on line 4—4 of Fig. 2.

Fig. 5 is a cross section taken on the line 5—5 of Fig. 1.

Fig. 6 is a cross section taken on the line 45 6—6 of Fig. 2.

Fig. 7 is a perspective view of a reinforcing member that is placed in that portion of the protecting device that overlies the back of the wrist.

Fig. 8 is a perspective view of a reinforcing member that is positioned in the protecting member over the base portion of the thumb and the joint between the thumb and wrist.

Fig. 9 is a perspective view of one of the reinforcing members that is utilized in the hand protecting device.

The main body portion of my improved hand protector includes an inner or palm member 10 and an outer or back member 11, which members are preferably formed of flexible leather; and formed integral with said inner and outer members are rearward extensions 12 that are adapted to overlie the back and the side portions of the wrist of the wearer.

The forward end of the members 10 and 11 are extended a short distance to form inner and outer sections 10^a and 11^a respectively that are adapted to overlie the knuckles between the palm portion of the hand and the fingers 70 and likewise to overlie the joints of the fingers immediately adjacent to the knuckles and arranged between these forwardly extending portions 10^a and 11^a is suitable padding 13 preferably curled hair or fibrous material.

Arranged on the inner forward extension 10^a is a transversely disposed strap, preferably of leather, that is secured by rows of stitching 14 to the member 10^a, thereby providing a series of finger receiving loops 15, and which construction leaves the outer portions of the fingers free and uncovered.

The ends of a transversely disposed strap 16 preferably of leather are secured to the side edges of the member 10 immediately to the rear of the finger receiving loops 15, which strap is designed to lie across the palm of the hand of the wearer and arranged on the face of this strap 16 is a transversely arranged substantially cylindrical padded member 17 that constitutes a filler or gripping member 90 when the hand is closed and clinched.

Arranged between the wrist covering portions 12 of the protector is a substantially rectangular section 18 of reinforcing material 95 such as light weight sole leather, the same being flexible to a certain degree and yet having sufficient stiffness to afford a considerable degree of protection to the back of the wrist of the wearer, and arranged between this reinforcing member 18 and the inner one of the members 12 is a layer 19 of padding such as curled hair or fibrous material. In order that the wrist covering portion of the protector may flex readily around the back of the wrist, I prefer to extend a row of stitching 20 lengthwise of the wrist covering portion along a medial line.

In order to further reinforce the wrist covering portion of the protector I arrange 110 between the reinforcing member 18 and the outer back section 12 a series of transversely

disposed reinforcing ribs 21, which may be composed of sole leather, composition, or flexible reeds, and these transversely disposed reinforcing members are retained in transversely disposed pockets that are formed by transversely disposed rows of stitching 22 that intersect the medial row 20, and which meet the rows of stitching 23 that unite the side edges of the wrist covering sections 12.

10 Thus when the protector is positioned on the hand the entire back and side portions of the wrist of the wearer are protected by the member 18 and the transversely disposed reinforcing ribs 21.

15 Formed integral with or secured to one side of the wrist covering portion of the protector is an elongated member composed of inner and outer sections 24 of flexible material such as leather, which member is designed to cover 20 the base portion of the thumb and that portion of the wrist immediately below the thumb and the forward portions of these members 24 are brought together to form a thumb covering member 25.

25 The inner section 26 of the thumb covering member consists in a single layer or section of flexible material and the outer end portion of the thumb covering member is provided with a relatively thin layer 27 of suitable 30 padding, which enables the end joint of the thumb of the wearer to be readily turned inward when the hand is closed.

35 Arranged within that portion of the thumb covering member that overlies the base of the thumb and the adjacent portion of the wrist is an elongated section 29 of reinforcing material such as light weight sole leather or the like and arranged between this section of reinforcing material and the inner layer of 40 the thumb covering member is a relatively thin layer 30 of suitable padding preferably curled hair or fibrous material.

45 Arranged between the reinforcing member 29 and the outer flexible wall of the thumb covering member is a series of short transversely disposed reinforcing members 31 that are practically duplicates of the reinforcing ribs 21.

50 Thus the entire thumb below the first joint and that portion of the wrist below the thumb is covered and protected by the parts 29, 30 and 31, and such protection minimizes the danger of throwing the thumb out of joint during bag punching operations.

55 Secured to the outer edge of the base or rear portion of the thumb covering portion of the protector and to the outer edge of the wrist covering portion of the protector are flaps 32 in which are arranged eyelets 33 that 60 are adapted to receive a lacing when the protector is positioned upon the hand, and secured to the inner face of the inner edge of one of these flaps is a flap 34, preferably of flexible leather, that underlies said flaps 32 65 and the lacing that secures said flaps, there-

by enabling the wrist portion of the protector to be laced over the inner portion of the wrist without undue discomfort.

Thus it will be seen that I have provided a hand and wrist protecting device that may be advantageously employed by boxers in training, and which protector is constructed so that it may be easily and quickly positioned upon the hand and when properly positioned the hand may be readily closed and clinched and the wrist covering portion of the protector being reinforced so as to give a marked degree of protection to the wrist joint and to the joint between the thumb and hand.

It will be understood that during training and particularly while punching the bag the wrist and thumb joints are the ones that are most liable to be injured or thrown out of joint and to minimize this danger, I have provided a protecting device having its wrist and thumb covering portions provided with padded surfaces that lie immediately against the surfaces of the wrist and the thumb and with reinforcing members disposed directly over said padded portions, and which arrangement is very effective in performing the functions for which it is intended.

It will be readily understood that minor changes in the size, form and construction of the various parts of my improved hand and wrist protector for boxers may be made and substituted for those herein shown and described without departing from the spirit of my invention, the scope of which is set forth in the appended claims.

I claim as my invention:

1. In a boxer's hand protector, a padded back hand covering member, a palm covering strap arranged transversely on the inside of said back covering member, a padded hand grip arranged on said palm covering strap, a wrist back covering member extending rearwardly from the hand back covering member, a single section of reinforcing material arranged in said wrist back covering member, and a series of transversely disposed reinforcing ribs overlying the reinforcing member in said wrist back covering member.

2. In a boxer's hand protector, a padded back hand covering member, a palm covering strap arranged transversely on the inside of said back covering member, a padded hand grip arranged on said palm covering strap, a wrist back covering member extending rearwardly from the hand back covering member, a single section of reinforcing material arranged in said wrist back covering member, a series of transversely disposed reinforcing ribs overlying the reinforcing member in said wrist back covering member, and pads on the inner surface of said wrist back covering member.

3. In a boxer's hand protector, a padded back hand covering member, a palm covering strap arranged transversely on the inside

- of said back covering member, a padded hand grip arranged on said palm covering strap, a wrist back covering member extending rearwardly from the hand back covering member, a single section of reinforcing material arranged in said wrist back covering member, a series of transversely disposed reinforcing ribs overlying the reinforcing member in said wrist back covering member, a thumb receiving member secured to one side of the protector and a reinforcing thumb back covering member extending rearwardly from said thumb receiving member and secured to the corresponding edge of the wrist back covering member.
4. In a boxer's hand protector, a back hand covering member, finger receiving loops projecting forwardly from the forward edge of said back hand covering member, a palm covering strap arranged transversely on the inside of said back hand covering member, a hand gripping member arranged on said palm covering strap, a wrist and thumb back covering member extending rearwardly from the back hand covering member, and transversely arranged reinforcing ribs in said wrist and thumb back covering member.
5. In a boxer's hand protector, a back hand covering member, finger receiving loops projecting forwardly from the forward edge of said back hand covering member, a palm covering strap arranged transversely on the inside of said back hand covering member, a hand gripping member arranged on said palm covering strap, a wrist and thumb back covering member extending rearwardly from the back hand covering member, and transversely arranged reinforcing ribs in said wrist and thumb back covering member.
6. A boxer's hand protector having a wrist back covering portion and a thumb back covering portion, sections of flexible reinforcing material arranged respectively in said wrist back and thumb back covering portions, and transversely disposed reinforcing ribs arranged in said wrist back and thumb back covering portions above the first mentioned reinforcing members.
7. In a boxer's hand protector, a back hand covering member, a wrist back covering member, a thumb back covering member, transversely disposed reinforcing ribs arranged in said wrist back and thumb back covering members, and cushioning pads arranged on the inner surfaces of said wrist back and thumb back covering members.
8. In a boxer's hand protector, a back hand covering member, a wrist back covering member, a thumb back covering member, transversely disposed reinforcing ribs arranged in said wrist back and thumb back covering members, cushioning pads arranged on the inner surfaces of said wrist back and thumb back covering members, a flap extending from one edge of the wrist back covering member, a flap extending from the outer edge of the thumb back covering member, and lace receiving eyelets seated in said flaps.

In testimony whereof I affix my signature.
GORDON TRAVERS.
